UNITED STATES PATENT OFFICE.

ALCANZO D. NEWCOMB, OF NORFOLK, VIRGINIA, ASSIGNEE, BY MESNE ASSIGNMENTS,
OF ONE-HALF TO RICHARD D. L. FLETCHER, OF CAPE CHARLES, VIRGINIA, AND
OF ONE-HALF TO ROBERT T. MARSH, OF RICHMOND, VIRGINIA.

OARLOCK FOR BOATS.

1,408,129.

Specification of Letters Patent. Patented Feb. 28, 1922.

Application filed February 21, 1917. Serial No. 150,161.

(GRANTED UNDER THE PROVISIONS OF THE ACT OF MARCH 3, 1921, 41 STAT. L., 1313.)

To all whom it may concern:

Be it known that I, ALCANZO D. NEWCOMB, a citizen of the United States, residing at Norfolk, in the county of Norfolk and State of Virginia, have invented certain new and useful Improvements in Oarlocks for Boats, of which the following is a specification.

My invention relates to new and useful 10 improvements in oar locks for boats.

The object of my invention is to provide an oar lock arranged in the side of the boat below the deck, so that the oars can be readily inserted and operated from below 15 the deck, and at the same time providing a watertight connection so that water can not enter the boat around the oar.

Another object of my invention is to provide an oar lock of this character which can 20 be readily removed and the opening for the oar quickly and tightly closed to prevent water entering the boat when the oars are not being used.

A still further object of my invention is 25 to provide an effective oar lock of this character having certain details of structure and combination of parts hereinafter more fully set forth.

In the accompanying drawings—

30 Figure 1 is a vertical sectional view of a portion of the side of the boat showing my improved oar lock and oar in side elevation;

Figure 2 is an enlarged vertical sectional 35 view of Figure 1;

Figure 3 is an enlarged vertical sectional view similar to Figure 2, showing the oar removed and the oar opening permanently closed by the stopper;

40 Figure 4 is an enlarged side elevation of the oar lock proper;

Figure 5 is a longitudinal sectional view of the oar, showing the means of attaching the flexible guard thereto.

45 Referring now to the drawings, 1 represents the side of a life boat having an opening 2 therein below the deck, and in which is secured my improved oar lock. This oar lock, as shown, consists of an oval casting 3, having an outwardly extending flange 4, which rests against the outer face of the side

1 of the boat around the opening 2 and secured thereto by means of rivets or bolts 5, as fully shown in Figures 2 and 3 of the drawings. The casting, as shown, extends 55 a considerable distance inwardly beyond the side of the boat and adjacent its outer end is provided with a flange 6 extending inwardly around its entire face, the purpose of which will be hereinafter more fully described.

The oar lock, as heretofore described, is an oval casting having an enlarged opening 7 at its upper end which is reduced at the center and lower end, as indicated at 7, by 65 means of the webs 9 and 10, which extend inwardly from the sides of the casting. The opening 7, at the upper end of the casting, allows the blade of the oar to be passed through the oar lock and the body of the 70 oar drops down into the opening 8 which forms the oar lock proper. From this description, it will be seen that provision is made for the insertion and removal of the oar, and, at the same time, provides an ap- 75 proximately U-shaped oar lock, in which the oar operates in the usual manner, as is readily understood.

The inwardly extending portion 10 of the casting 1, beyond the flange 6, is provided 80 on its outer periphery with a semi-circular groove 11 in which is secured the outer end of the water-proof hood 12. This hood, as shown, is secured in the groove 11, by means of the split ring 13. The outer end of the 85 water-proof hood 12 is secured to the oar 14 in a similar manner, which I shall now proceed to describe. The oar 14 consists of the main body portion 15 having removably secured at one end the handle 16. This han- 90 dle, as shown, is provided with a reduced extension 17 entering the socket 18 in the portion 15 and held therein by means of the pin 19. The main body portion 15 of the oar is provided with a reduced portion 20 over 95 which slides the ring 21 having an annular groove 22 in which the inner end of the hood 12 is secured by the split ring 24. Surrounding the reduced portion 20, on the out- 100 side of the ring 21, is an elongated sleeve 23 which extends to the end of the main body portion 15. The end of the main body por-

tion is provided with a screw-threaded socket 25 into which is screwed the extension 26 of the blade portion 27. The shoulder 28 of the blade portion 27, bears against the 5 end of the sleeve 23 and tightly clamps and holds the ring 21 in position on the main body portion of the oar. By this structure, it will be seen that the blade portion 27 of the oar can be unscrewed and the sleeve 23 10 and ring 21 can be removed without breaking the water-tight connection between the water-proof apron and the ring 21.

The inwardly extending portion 10 beyond the semi-circular groove 11, is provided with two oppositely arranged openings 29 and 30. The stopper for closing the oar lock opening, when the oar is not in use, consists of a plate 31 fitting within the extension 10 and carrying on its outer face a 15 packing 32 resting against the inner face of the flange 6. This packing is secured to the plate 31 by means of a ring 33 on the outside of the annular flange, and the said ring being secured to the plate by means of 20 bolts or rivets 34. Swiveled to the inner end of the plate 31 is a screw 35 which passes through a threaded opening in the transverse bar 36. The outer ends of the transverse bar are provided with reduced 25 portions 37 and 38 which pass into the openings 29 and 30 of the portion 10 of the casting. The reduced portion 37 of the bar 36 is of a greater length than the portion 38, so that the portion 37 can be inserted through the 30 opening 29 far enough to allow the portion 38 to enter the inner periphery of the portion 10 of the casting and the bars then move transversely to allow the portion 28 to enter the opening 30. The screw 35 is provided 35 at its inner end with a handle 39, whereby the screw is rotated for forcing the plate 31 inwardly to cause the packing 32 to tightly engage the inner face of the flange 6 and thus form an absolutely water-tight joint to 40 prevent any water entering the boat.

From the foregoing description, it will be seen that I have provided an oar lock which is adapted to be used through the side of the boat from below the deck and which can be 45 readily removed or inserted and at the same time provides means whereby water can not enter the boat when the oar is being used and the oars are so constructed that they can be disjointed for the purpose of storing 50 and yet provide a strong and durable oar. I also provide means whereby when the oar is removed the oar lock is tightly sealed or closed to prevent water entering the boat and making all of the parts of a simple construction easily placed in position for 55 removal.

Having thus described my invention, what I claim as new and desire to secure by Letters Patent, is:

65. 1. The combination with a boat, of an oar

lock carried thereby below the deck, and having an enlarged opening to allow the blade of the oar to pass through the lock.

2. The combination with a boat, of an oar lock carried thereby below the deck, and 70 having an enlarged opening to allow the blade of the oar to pass through the lock, and means for forming a water-tight connection between the oar and oar lock.

3. The combination with a boat, of an oar 75 lock carried by the side of the boat below the deck, and having an enlarged opening at its upper end to allow the blade of the oar to pass through the lock, and means for forming a water-tight connection between 80 the oar lock and the oar.

4. The combination with a boat, of an oar lock carried by the side of the boat below the deck and having an enlarged opening at 85 its upper end to allow the blade of the oar to be inserted through the oar lock, means for forming a water-tight connection between the oar lock and the oar, and means for closing the opening in the oar lock when the oar is removed. 90

5. The combination with a boat, of an oar lock carried by the side of the boat below the deck and having an enlarged horizontal opening at its upper end communicating with a central reduced opening, an oar in 95 said reduced central portion, and means for forming a water-tight connection between the oar lock and the oar.

6. The combination with a boat, of an oar lock carried by the side of the boat below 100 the deck and having an enlarged opening at its upper end to allow the blade of the oar to be inserted through the oar lock, and a central reduced opening communicating with the large opening, an oar in said reduced 105 central portion, and a flexible hood removably secured to the oar and the oar lock on the inside of the side of the boat.

7. The combination with a boat, of an oar lock carried by the side of the boat below the 110 deck, and having an enlarged opening at its upper end to allow the blade of the oar to be inserted through the oar lock; and a central reduced opening communicating with the large opening, an oar resting in the reduced central opening, a flexible hood secured to the oar lock and having its opposite end removably secured to the oar, whereby 115 a tight joint is formed to prevent water entering the boat around the oar. 120

8. The combination with a boat, of an oar lock carried by the side of the boat below the deck and having an enlarged opening in its upper end to allow the blade of the oar to be inserted through the oar lock, 125 and a stopper removably secured in the oar lock and closing the opening when the oar is removed.

9. The combination with a boat, of an oar lock carried by the side of the boat below 130

the deck and having an enlarged opening to allow the blade of the oar to be inserted through the lock, an annular flange carried by the inner face of the oar lock, and a removable stopper adapted to engage the annular flange to close the oar lock and form a water-tight connection, substantially as shown and described.

10. The combination with a boat, of an oar lock carried by the side of the boat below the deck and having an enlarged opening at its upper end to allow the blade of the oar to be inserted through the oar lock, and a central reduced opening communicating with the enlarged opening, an oar resting in the reduced central opening, a removable blade carried by the oar and securing a hood to the oar, and means for securing the opposite end of the hood to the inner face of the 20 oar lock, whereby water is prevented from passing into the boat around the oar.

11. The combination with a boat, of an oar lock carried by the side of the boat below the deck and having an enlarged opening at 25 its upper end to allow the blade of the oar to be inserted through the oar lock, and a central reduced opening communicating with the enlarged opening in which the main body of the oar rests, an inwardly extending 30 sleeve carried by the oar lock and having oppositely arranged openings, an inwardly extending flange carried by the said sleeve, a plate having a packing resting against the flange, a screw swiveled to the said plate and 35 a transverse bar screwed on the screw and having its end adapted to interlock in the opening whereby the plate is forced against the flange to tightly close the oar lock when the oar is not in use.

40 12. The combination with a boat, of an oar lock carried by the side of the boat below the deck, an oar removably mounted in said oar lock and comprising a main body portion, a handle detachably secured thereto, 45 one end of the body portion having a reduced portion, a ring sliding on said reduced portion, a hood secured to said ring and having its opposite end secured to the oar lock, a sleeve on the reduced portion of the body 50 portion and engaging the ring, and a blade

screwed within the outer end of the body portion and having a flange engaging the sleeve whereby the ring is removably secured to the oar, substantially as shown and described.

55

13. The combination with a boat, of an oar lock carried by the side of the boat below the deck and having an enlarged horizontal opening at its upper end to allow the blade of the oar to be inserted through 60 the oar lock, and a central reduced opening communicating with the enlarged opening in which the main body portion of the oar rests, an inwardly extending sleeve carried by the inner face of the oar lock and having oppositely arranged openings, an inwardly extending flange carried by the said sleeve, a plate having a packing resting against the flange, a screw swiveled to the said plate, a transverse bar screwed on the screw and 65 having its ends adapted to interlock in the openings, means for securing an apron to the sleeve in beyond the openings, and means carried by the apron for securing it to the oar when the oar is inserted through the oar 70 lock.

14. An oar lock, comprising a body portion having an oar receiving opening and an enlarged opening communicating therewith to allow the blade of the oar to pass there- 80

15. An oar lock, comprising a body portion having an oar receiving opening and an enlarged opening at its upper end communicating with the oar opening to allow 85 the blade of the oar to pass through the lock.

16. An oar lock, comprising a body portion having an oar receiving opening and an enlarged opening at its upper end communicating with the oar opening to allow 90 the blade of the oar to pass through the lock, and means for forming a water-tight connection between the oar lock and the oar.

In testimony whereof I affix my signature 95 in the presence of two witnesses.
